(57) **CLAIM**

The ornamental design for a wireless charger, as shown and described.

DESCRIPTION

FIG. 1 is a front view of a wireless charger showing our new design with aspects of a charger omitted for clarity purposes; FIG. 2 is perspective view of a first embodiment of a wireless charger bearing the design of FIG. 1; FIG. 3 is a front view thereof; FIG. 4 is a perspective view of second embodiment of a wireless charger bearing the design of FIG. 1; FIG. 5 is a top view thereof; FIG. 6 is a perspective view of a third embodiment of a wireless charger bearing the design of FIG. 1; FIG. 7 is a front view thereof; FIG. 8 is a perspective view of fourth embodiment of a wireless charger bearing the design of FIG. 1; and, FIG. 9 is a front view thereof.
The solid black surface shading depicting the two generally centrally located trapezoid shapes and the outer radiating line segments represent a color contrast with the unshaded region. The broken lines in the figures are for the purpose of illustrating portions of the wireless charger that form no part of the claimed design.
